United States Patent Office

Des. 189,558
Patented Jan. 3, 1961

189,558

PROJECTION MACHINE

John T. Armbruster, Niagara Falls, and Henry T. Wilton,
Buffalo, N.Y., assignors to American Optical Com-
pany, Southbridge, Mass.

Filed July 26, 1960, Ser. No. 61,529

Term of patent 14 years

(Cl. D61—1)

FIG. 1

FIG. 2

FIG. 3

FIG. 4

Fig. 1 is a perspective view showing the front and one side of a projection machine showing our new design;

Fig. 2 is a perspective view showing the front and other side thereof;

Fig. 3 is a top plan view thereof; and

Fig. 4 is a rear elevational view thereof.

We claim:

An ornamental design for a projection machine, as shown and described.
